(57) CLAIM

The ornamental design for a wick trimmer, as shown and described.

DESCRIPTION

FIG. 1 depicts a perspective view of the invention, from above.

FIG. 2 depicts a perspective view of the invention, from below.

FIG. 3 depicts a top plan view of the invention of FIG. 1.

FIG. 4 depicts a bottom plan view of the invention of FIG. 1.

FIG. 5 depicts a top plan view of the invention of FIG. 1, in an open configuration.

FIG. 6 depicts a side elevation view of the invention of FIG. 1; and,

FIG. 7 depicts a side elevation view of the other side of the invention of FIG. 1.
